UNITED STATES PATENT OFFICE

98,068

DESIGN FOR AN AUTOMOBILE RADIATOR ORNAMENT

Franklin Q. Hershey, Detroit, Mich., assignor to
General Motors Corporation, Detroit, Mich., a
corporation of Delaware

Application September 30, 1935, Serial No. 58,757

Term of patent 7 years

To all whom it may concern:

Be it known that I, Franklin Q. Hershey, a citizen of the United States and a resident of Detroit, county of Wayne, State of Michigan, have invented a new, original, and ornamental Design for Automobile Radiator Ornament, of which the following is a specification, reference being made to the accompanying drawing, forming a part thereof.

In the drawing:

Figure 1 is a side elevation showing my design, and Figures 2 and 3 are, respectively, a top plan view and a front elevation.

I claim:

The ornamental design for an automobile radiator ornament as shown.

FRANKLIN Q. HERSHY.
